UNITED STATES PATENT OFFICE

GEORGE N. TAYLOR, OF EAST PROVIDENCE, RHODE ISLAND, ASSIGNOR TO UNIVERSAL WINDING COMPANY, OF BOSTON, MASSACHUSETTS, A CORPORATION OF MASSACHUSETTS

SUPPLY-HOLDER

Application filed January 30, 1930. Serial No. 424,682.

This invention relates to supply-holders for holding cops, bobbins or other forms of packages of yarn, thread and the like to deliver the material to winding machines or 5 other textile apparatus.

In the following specification and claims the term "bobbin" is to be interpreted in a generic sense to apply to any preferred form of supply, and the term "yarn" is employed 10 in a broad sense to designate all varieties of strand material.

One object of the invention is to provide a supply-holder which will facilitate and expedite the doffing of spent bobbins and the 15 placing of fresh bobbins in delivering position.

Another object of the invention is to provide a device of the type specified wherefrom the spent or exhausted bobbins may be doffed 20 or ejected by simply pressing a button or push-rod.

Another object of the invention is to provide a device of the type specified to which the bobbins may be applied by simply dropping 25 them into a chute or onto a runway whereby to cause them to be carried into delivering position.

Another object of the invention is to provide a device of the type specified having 30 means for continuously supplying bobbins in position to be dropped into the chute to apply them to the holder.

Another object of the invention is to provide a device of the type specified which is 35 operated automatically to carry the bobbins into delivering position after they have been dropped onto the holder.

Further objects of the improvement are set forth in the following specification which describes a preferred form of construction of the invention, by way of example, as illustrated by the accompanying drawings. In the drawings:

Fig. 1 is an end view of a conventional type of winding machine showing the present improved supply-holder as applied to use therewith;

Fig. 2 is an enlarged view of the supply- 50 holder showing its bobbin-holding means re-

leased and thrown into position to doff the spent bobbin or empty yarn-carrier;

Fig. 3 is a similar view showing the device set for receiving a fresh bobbin;

Fig. 4 is a still further enlarged plan view 55 of the bobbin-holding means, shown as part-sectional on line 4-4 of Fig. 3;

Fig. 5 is a front view of the same, part-sectional on line 5-5 of Fig. 3;

Fig. 6 is a reduced detailed view of the 60 mounting for the supply-holder;

Fig. 7 is a plan view of the chute which receives the bobbin;

Fig. 8 is a plan view of the guiding-rod 65 or run-way for the bobbin; and

Fig. 9 is a detailed view of the latch and pawl which control the operation of the bobbin-holder.

In general, the present invention comprises a spindle or other means for holding a bobbin 70 or the like in delivering position, a chute or runway for transferring the bobbin to the spindle, means for manually operating the spindle to doff or eject a spent bobbin, and automatically-operated means to return the 75 spindle into position to receive a fresh bobbin and to thereafter move it into delivering position. The invention also contemplates the use of a traveling belt or conveyor associated with the bobbin-receiving chute to continuously supply bobbins in position to be placed in the chute to transfer them to delivering position.

The invention as herein shown is applied 80 to use on a winding machine for winding thread, yarn and other strand material, but the device is also adapted for use on other types of textile apparatus in which yarn or the like is transferred from one carrier to another in various and sundry processes of 85 the textile art.

Referring to Fig. 1 of the drawings, the winding machine as herein shown is supported on legs or standards 2 and comprises a plurality of heads or units surmounting a 90 horizontal bed or frame 3 extending between the legs. The winding mechanism as herein illustrated by way of example comprises a drum or drive-roll 5 for rotating the cop or package which is wound on a mandrel or 95

cop-holder 6. The cop-holder 6 is carried at the end of a swinging arm 7 which is pivoted at 8 to an upright 9 on the machine frame, the package being thus supported with its periphery in contact with the drive-roll 5 to 5 adapt it to be driven therefrom as its axis recedes from the roll during the increase in diameter of the winding. The strand of yarn or other material, indicated at y , is traversed longitudinally of the cop-holder 6 during the 10 rotation of the latter by means of a reciprocating thread-guide 10. The thread-guide 10 is mounted to slide on horizontal tracks or ways 11 and 12 and connected thereto is a bowl or roller 13 which engages a helical 15 groove 14 in the rotating cam 15 whereby to reciprocate the guide. The construction of the winding mechanism as above described is well known to those versed in the present 20 art and is therefore not herein illustrated in detail.

Each unit of the winding machine is usually provided with a tension-device for applying resistance to the draft on the yarn as it feeds to the cop or package being wound, 25 and the present drawings illustrate a disk-tension for this purpose. In Fig. 1 the tension-device is shown as mounted on a bracket 17 which is bolted to the front of the frame 30 of the winding machine at 18 and provided with a horizontal shelf or rest 19 supporting a vertical spindle 20. A pair of tension-disks 21 are mounted on the spindle 20, and a weight-holder 22 slidable on the spindle 25 thereabove carries a suitable number of weights 23 which apply pressure to hold the tension-disks against the strand of yarn drawing therebetween. A spring 24 is preferably interposed between the weight-holder 22 and the upper tension-disk to provide for 40 the separation of the tension-disks when knots and enlargements pass therethrough without moving the tension-weights.

The strand of yarn y leads through an 45 opening or guide-eye 26 at one side of the shelf 19 and draws across the top of the shelf to feed between the two tension-disks 21. From the tension-disks the strand y draws 50 through a suitable slub-catcher 27, as usually provided, and thence leads to the thread-guide 10 to be fed therefrom and traversed thereby onto the cop or package being wound.

In delivering yarn or other strand material from cops, bobbins and other types of headless packages, the strand is usually drawn off over the end of the package and for winding machines the supplies are generally arranged below the winding units with their axes in line with the point to which the yarn 55 draws as it feeds through the tension-device. In the present application of the invention to a winding machine the supply-holders, one for each winding unit, are supported from a horizontal rod 28 which extends between 60 arms or brackets 29 attached to the legs 2.

As shown in Fig. 1, the brackets 29 are fastened to the web of the legs 2 by means of clamps 30 secured in place by bolts 31, and the rod 28 is held in hubs 32 at the ends of the brackets by means of set-screws 33.

A series of inclined arms or brackets 34 are bolted to the front of the frame of the winding machine to extend outwardly above the brackets 29. The brackets 34 serve as upper supports for the chutes and runways into which the bobbins are placed and down which they slide to apply them to the spindles or other holding means which are automatically operated to carry them into delivering position. As shown in Figs. 1 and 2 of the drawings a trough 35 is carried at the outer ends of the arms 34, being attached thereto at 36 and extending horizontally the whole length of the winding machine. Extending through the trough 35 is a conveyor-belt 37 which passes around suitable pulleys 38 at the ends of the machine and is thereby continuously driven to travel it longitudinally of the trough. The traveling belt 37 is provided as a means for conveying bobbins from a 80 source of supply into convenient position to be picked up by the operator and placed in the chute which delivers them to the supply-holder. The bobbins may be fed to the conveyor-belt from a suitable hopper, not shown, 85 or by manual means as desired.

The bobbin-chute 40 comprises a pair of wing-like sections or plates 41 curved to conform to the shape of the bobbin B and supported on upright inclined rods 42 and 43. The upper ends of the rods 42 and 43 are held in bosses or hubs 44 projecting from an arm or bracket 45 which is attached to the trough 35 by means of a screw or screws 46 extending through an overhanging flange 47 on the side of the trough. As shown in Fig. 3, the rods 42 and 43 are secured in the hubs 44 by means of set-screws 48 and the plates or wings 41 have hubs 49 surrounding the rods and fastened thereto by means of set-screws 50, see 110 Fig. 7. The plates 41 are thus rigidly attached to the rods at their upper ends while their lower ends have ears or projections 51 bearing against the sides of the rods to hold them in position thereon. The sides of the 115 chute 40, comprising the wings or plates 41, are flared outwardly at the top to facilitate the insertion of the bobbins thereinto and as each bobbin slides through the chute it is guided by the two rods 42 and 43 in the manner as later more fully explained. It will be noted by reference to Fig. 7 that the rod designated 42 is of hollow or tubular construction whereby to adapt it to receive a plunger-rod 60 which is slidable therein for 120 a purpose as later explained.

The lower ends of the rods 42 and 43 are held in a bracket 53 which is mounted on the horizontal rod 28, before referred to. The bracket 53 has a hub 54 encircling the rod 28 130

and secured fast thereto by means of a set-screw 55, see Figs. 4 and 6. Projecting from the hub 54 are two arms 56 formed with bosses at their ends bored to receive the rods 42 and 43 which are secured fast therein by means of set-screws 57, see Fig. 5.

The plunger-rod 60 extends downwardly through the hollow rod 42 and is bent at its lower end to form a right-angled arm 61 which projects outwardly between two lugs 62 on the under side of one of the arms 56 and then extends laterally in the direction of the rod 28. The two lugs 62 prevent the rod 60 from turning within the hollow rod 42 and the arm 61 provides means for operating the control-mechanism of the bobbin-spindle in the manner as later explained. Secured to the upper end of the plunger-rod 60 is a finger-piece or push-button 65, beneath which is a helical spring 66 coiled around the rod. The spring 66 bears against a washer 64 arranged above the boss 44 in which the hollow rod 42 is held and serves as a means for normally holding the plunger-rod in raised position, as shown in Fig. 1, with its arm 61 bearing against the bottom of the bracket 53.

The bracket 53 serves as a support for a bearing-member 67 which carries a pivot for rockably mounting the bobbin-spindle 70. As shown most clearly in Figs. 4, 5 and 6, the bracket 53 is provided on one side with a rectangular portion 71, to which is bolted the member 67. The member 67 is formed with a longitudinal slot 68 through which extends a bolt 72 screwed into the bearing 71. The purpose of the slot 68 is to provide for lateral adjustment of the member 67 which supports the spindle 70 so that the latter may be set at different distances from the rods 42 and 43 in accordance with the diameter of the bobbins being used as supplies; it being understood that the bobbins slide down the runway formed by the rods 42 and 43 to impale them on the spindle 70.

On the bottom of the member 67 is a hub 73 which receives the reduced end of a pivot-stud 75 held in place in the hub by a set-screw 76, see Fig. 5. Pivoted to turn on the headed end of the stud 75 is a disk-like member 77 formed on its periphery with a socketed bearing 78 in which the end of the spindle 70 is stepped and held in place by means of a set-screw 79. The disk 77 is provided with a radial arm 80 formed with a weight 81 at its end which acts to rotate the disk on its pivot to move the spindle 70 from normal delivering position, shown in Fig. 1, down into inclined position as illustrated in Fig. 2, whereby to eject the spent bobbin-tube or yarn-carrier *b* off from its end. The disk or rotatable member 77 is maintained with the spindle 70 in vertical position while the bobbin *B* is delivering its material by means of a latch 85 which engages a suitable de-

tent-shoulder 86 on the periphery of the disk, see Fig. 1.

The latch 85, shown in detail in Fig. 9, is pivoted on a pin 87 fastened in a boss at the rearward end of the member 67 by means of a set-screw 88, see Fig. 6. The latch 85 is formed with a weighted arm 89 projecting rearwardly from its hub and is provided with a forwardly and upwardly curved arm 90 which terminates in a fork 91, shown most clearly in Fig. 4. The fork 91 straddles the sides of the spindle 70 when the latter is either in vertical or slightly inclined position to adapt the latch 85 to be struck by the end of the bobbin-tube or carrier *b* as the latter slides down the runway and is impaled on the spindle. On the underside of the latch 85 is a tooth or projection 92 which engages with the detent shoulder 86 on the periphery of the disk 77.

The periphery of the disk 77 is formed with a second notched shoulder 93 which is engaged by the toe 94 of a pawl 95 pivoted on the pin 87 on which the latch 85 is mounted. The pawl 95 has an arm extending rearwardly and downwardly from its pivot which provides a weight for holding its toe-portion 94 against the periphery of the disk 77. The upper forward edge 96 of the pawl 95 is adapted to be engaged by an abutment or shoulder 97 on the side of the latch 85, whereby when the latter is rocked by the engagement of the bobbin *b* with its forked end 91 the pawl 95 will be released from the notch 93 in the disk 77 to allow the weight 81 on the disk to turn the latter to shift the spindle 70 from the position shown in Fig. 3 to that illustrated in Fig. 1.

It is to be noted that the arm 61 of the plunger-rod 60 is normally maintained in position above the weighted arm 89 of the latch 85 so that when the finger-piece or push-button 65 is pressed to slide the rod downwardly the arm will act against the top of the weight to rock the forward end of the latch 85 upwardly to release its detent-projection 92 from the shoulder 86 on the disk 77. As these detents are released the disk 77 will turn under the action of its weight 81 to swing the spindle 70 from the position shown in Fig. 1 to that of Fig. 2. The method of operation of the complete device is as next explained.

Assuming that a bobbin *B* is in place on the spindle 70 of the supply-holder, as shown in Fig. 1 of the drawings, with the strand *y* therefrom led up through the guide-eye 26 and thence drawn through the tension-device to the thread-guide 10, the winding proceeds in the usual manner. The end of the strand *y* being attached to the cop-holder 6 the latter is lowered to place its periphery in contact with the rotating drive-roll 5 and the roll will therefore frictionally drive the cop-holder to wind the yarn thereon with 130

the thread-guide 10 traversing the strand back and forth to deposit it in helical coils which build up in layers to form the package. As the winding proceeds and the yarn 5 is taken off from the bobbin B, eventually the end will run out and the operation of the machine is arrested through the automatic action of instrumentalities as usually provided, but not herein shown or described.

10 The spindle 70 is normally maintained in vertical relation to support the bobbin B in delivering position by the action of the weight 81 which holds the disk 77 with its notch 86 engaged by the detent-projection 92 on the latch 85, see Fig. 1.

When it is observed that the yarn on the bobbin B is almost exhausted the operator assumes a station at the front of the supply-holder and immediately the winding has 20 been arrested the push-button or finger-piece 65 is pressed downwardly to project the plunger-rod 60 through the hollow rod or tube 42. The downward sliding movement of the rod 60 carries its arm 61 against the

25 weighted tail-piece or arm 89 of the latch 85 to rock the latter into the position shown in Fig. 2 whereby to release its detent-projection 92 from the shoulder 86. As the disk 77 is thus released from the latch 85 the 30 weighted arm 80 will turn it on its pivot to swing the spindle 70 to the right and downwardly into the position illustrated in Fig. 2 of the drawings. It will be understood that as the weight 81 swings across center its momentum will carry it therebeyond, its motion being augmented by the weight of the spindle 70 and the bobbin-tube b to continue the clockwise rotation of the disk 77 until the spindle is inclined 35 at such an angle that the tube b will drop off from its end. A suitable bobbin-box or other receptacle, not herein shown, is usually placed below the supply-holders to receive the empty bobbin-tubes or yarn-carriers as they are ejected therefrom.

Now, after the disk 77 has been turned into the position shown in Fig. 2 and the bobbin-tube doffed or ejected therefrom, the momentum of the weight 81 is finally overcome 50 and the arm 80, acting as a pendulum, swings the disk back in the opposite direction. This return movement of the weighted arm 80 carries the disk 77 around until the toe 94 on the pawl 95 snaps into engagement with the

55 notch 93 in the edge of the disk. The disk 77 is thereby locked in the position illustrated in Fig. 3 of the drawings to hold the spindle 70 in parallel relation to the rods 42 and 43 which form the runway for the bobbin. Stated briefly, after the doffing of the empty tube b the disk 77 is automatically swung back under the action of the weight 81 to align the spindle 70 with the axis of the bobbin-chute 40.

60 It will be understood that immediately the

detent-latch 85 has been disengaged from the shoulder 86 on the disk 77 the finger-piece 65 is released so that the spring 66 will return the plunger-rod 60 to first position as shown in Figs. 1 and 3. As the spindle 70 70 is swung back into position in line with the chute 40 the operator picks a bobbin off from the traveling belt or conveyor 37 and entering it through the top of the chute, releases it to permit it to slide down the runway. 75 As the bobbin B slides down on the rods 42 and 43 the end of the bore in the tube b, which is usually beveled or belled outwardly as shown at x in Fig. 3, rides over the rounded end of the spindle 70 and is impaled thereon. The bobbin B gains momentum as it slides down the runway and aided by the action of gravity the end of the tube b strikes against the forked end 91 of the latch 85 with some force. This impact of 80 the bobbin against the latch 85 swings its forked end 91 downwardly with a quick action and its lateral shoulder or abutment 97 strikes against the forward end 96 of the pawl 95 to rock the latter to release its toe 94 from engagement with the notch 93 in the disk 77. The disk 77 is thereby released to be acted upon by its weighted arm 80 which tends to swing it in a clockwise direction. In the meantime, however, the latch 85 has 85 been carried down until its projection 92 brings up against the periphery of the disk 77 and consequently the disk is turned only to a slight extent, or until the shoulder 86 on its edge brings up against the projection 92 on the latch. This last turning movement of the disk 77 carries the spindle 70 90 into vertical position where it is held locked by the latch 85 to maintain the bobbin B erect with its axis alined with the guide-eye 26 of the tension-device, see Fig. 1. It will thus be apparent that after the doffing of the empty bobbin-tube b through the manual operation of the push-rod 60 the bobbin-holder is first turned into position to receive 95 a fresh bobbin as it slides down the runway, and then the action of impaling the bobbin on the spindle 70 releases the disk 77 to permit the spindle to be carried back into vertical position.

100 It will be observed from the foregoing that the invention provides a bobbin-holder which is almost entirely automatic in operation, the operator having only to press the button to effect the doffing of the empty bobbin-tube and to then place a fresh bobbin in the chute to cause it to be impaled on the spindle and carried into delivering position.

105 The bobbin-chute is placed conveniently in advance of the tension-device of the winding machine so that as the operator drops the bobbin thereinto the end of the yarn may be held in the fingers and drawn into the guide-eye 26 and across the rest 19 to be spliced to the trailing end from the package being 110

wound. It will be observed by reference to Fig. 7 that the side of the chute 40 is open between the edges of its wings 41 so that the yarn may be passed therethrough as it is carried to the tension-device. The tension-device and slub-catcher are preferably of the self-threading type so that immediately the winding is started the draft on the yarn will cause it to be drawn between the tension-disks and into the slot of the slub-catcher without further attention on the part of the operator.

The provision of the traveling conveyor adjacent the several bobbin-chutes arranged along the front of the machine further facilitates and expedites the handling of the supplies, the bobbins being continuously fed into position at the front of the bobbin-chutes so that the operator has only to lift them off therefrom without stooping or reaching. The invention thus provides for a substantial saving in the time usually spent in doffing the spent bobbins and supplying fresh ones in their place, it requiring only a few seconds to drop the bobbin into the chute and draw its end to the winding mechanism. Furthermore, the operator does not have to bend over to lift the bobbin-tube off from its spindle and thereafter place a fresh bobbin thereon, and thus less effort and energy is used and the operator's strength conserved for other duties.

Recently there has been a notable trend in the winding art to greatly increase the speed of operation of the winding machines and, obviously, when the machines are stopped for replenishing the supplies the loss of production is correspondingly greater. Consequently, a saving in the time required for doffing spent supplies and placing new bobbins in delivering position is reflected in a proportionate increase in the productiveness of the machine. The present invention therefore provides an important improvement in the art as economizing in time and labor and increasing the productive capacity of the machine.

While I have herein shown the invention as embodied in a preferred form of construction, and as applied to a winding process, various modifications may be made in the form and arrangement of the parts of the device and in its method of application to other processes without departing from the spirit or scope of the invention. Therefore, without limiting myself in this respect, I claim:

1. A device of the type specified comprising means for holding a bobbin, manually-controlled means for tilting the holding-means into inverted position to cause a spent bobbin to slide off therefrom, and means for automatically returning the holding-means into position to receive a fresh bobbin.

2. A device of the type specified comprising means for holding a bobbin, means for

moving the holding-means to doff a spent bobbin therefrom, means for returning the holding-means into position to receive a fresh bobbin, and means operated by the placing of a bobbin on the holding-means to carry the bobbin into delivering position.

3. In a device of the type specified, the combination of a chute for bobbins, a bobbin-holder arranged in position to receive a bobbin as it delivers from the chute, and means for moving the bobbin-holder into inverted position to eject a spent bobbin therefrom.

4. In a device of the type specified, the combination of a chute for bobbins, a bobbin-holder arranged in position to receive a bobbin as it delivers from the chute, means for moving the bobbin-holder into inverted position to eject a spent bobbin therefrom, and means for returning the holder into position to receive a fresh bobbin from the chute.

5. In a device of the type specified, the combination of an inclined chute for bobbins, a bobbin-holder arranged beneath the chute, means for retaining the holder in position to receive a bobbin delivered thereto from the chute, and means operated by the application of the bobbin to the holder to carry said bobbin into delivering position.

6. In a device of the type specified, the combination of an inclined chute for bobbins, a bobbin-holder arranged beneath the chute, means for retaining the bobbin-holder in position to receive a bobbin delivered thereto from the chute, means operated by the application of the bobbin to the holder to carry said bobbin into delivering position, and means for operating the bobbin-holder to eject a spent bobbin therefrom and to thereafter return the bobbin-holder into position to receive a fresh bobbin from the chute.

7. In a device of the type specified, the combination of an inclined chute for bobbins, a bobbin-holder arranged beneath the chute, means for retaining the holder in position to receive a bobbin delivered thereto from the chute, means operated by the application of the bobbin to the holder to carry said bobbin into delivering position, manually-operable means for actuating the bobbin-holder to doff a spent bobbin therefrom, and means for automatically returning the bobbin-holder into position to receive a fresh bobbin from the chute.

8. In a device of the type specified, the combination of a tiltable spindle for holding bobbins, means for tilting said spindle into inverted position to eject a spent bobbin therefrom, and automatically operated means for returning said spindle to position to receive a fresh bobbin.

9. In a device of the type specified, the combination of a tiltable spindle for holding bobbins, detent-means for maintaining said spindle in substantially erect position during the delivery of the yarn from the bobbin,

means to release the detent-means, and means rendered operable by the release of the detent-means to tilt the spindle downwardly into inverted position to eject the spent bobbin therefrom and to return the spindle into position to be engaged by the detent-means to adapt it to receive a fresh bobbin.

10. In a device of the type specified, the combination of a tiltable spindle for holding bobbins, detent-means for normally maintaining the spindle in substantially erect position during the delivery of the material from the bobbin, manually-operable means for releasing the detent-means, and a weight for tilting the spindle to cause the spent bobbin to be doffed therefrom, said weight operating as a pendulum to return the spindle to position to reengage the detent-means.

11. In a device of the type specified, the combination of a chute for bobbins, a tiltable spindle arranged below the chute to adapt to receive a bobbin delivered therefrom, detent-means for holding the spindle in aligned cooperative relation with the chute, means actuated by the application of a bobbin to the spindle to release the detent-means, means operating upon the release of the detent-means to rock the spindle into vertical position, and manually-controlled means for tilting the spindle downwardly to doff a spent bobbin therefrom and to thereafter return the spindle into alignment with the chute to be held by the detent-means.

12. In a device of the type specified, the combination of a chute for bobbins, a tiltable spindle arranged below the chute to adapt it to receive a bobbin delivered therefrom, detent-means for holding the spindle in cooperative relation with the chute, means actuated by the application of a bobbin to the spindle to release the detent-means, means operating upon the release of the detent-means to rock the spindle into vertical position, detent-means for maintaining the spindle in vertical position during the delivery of the yarn from the bobbin, manually-operable means for releasing the second detent-means, and means for tilting the spindle downwardly to doff a spent bobbin therefrom and to thereafter return the spindle into alignment with the chute to be held by the first detent-means.

13. In a device of the type specified, the combination of a runway, means for holding a bobbin delivered thereto from the runway, means operated by the placing of the bobbin on the bobbin-holder to carry said bobbin into delivering position, means for operating the bobbin-holder to eject a spent bobbin therefrom, and means for returning the bobbin-holder into cooperative relation with the runway to adapt it to receive a fresh bobbin therefrom.

14. In a device of the type specified, the combination of a tiltable spindle for holding

bobbins, a runway for delivering a bobbin onto the spindle, a latch for holding the spindle with the bobbin in delivering position, a push-rod for operating the latch to release the spindle, and means for tilting the spindle downwardly into inverted position to doff an empty bobbin therefrom.

15. In a device of the type specified, the combination of a pivoted bobbin-holder having a detent, a latch engaging the detent on the bobbin-holder to maintain the bobbin in delivering position, a push-rod for releasing the latch, and a weight on the bobbin-holder for turning it into position to doff a spent bobbin therefrom, said weight acting to thereafter return the bobbin-holder to first position.

16. In a device of the type specified, the combination of a pivoted member provided with detents, a spindle mounted on said member to adapt it to hold bobbins, a pawl engaging one of the detents on the member to maintain the spindle in inclined relationship, a latch adapted to be operated by the placing of a bobbin on the spindle to release the pawl, said latch having means for engaging a second detent on the member to hold it with the spindle in substantially vertical position, a weighted arm on the pivoted member, and means for operating the latch to release the pivoted member whereby its weight will turn it into position to tilt the spindle to doff a spent bobbin therefrom and thereafter return the member into first position to be held by the pawl.

17. In a device of the type specified, the combination of a pair of inclined rods one of which is of tubular construction, a bobbin-chute arranged at the upper end of the rods, a bobbin-holder pivoted at the lower end of the rods and formed with detents, a pawl adapted to engage with one of said detents, a latch for engaging the other detent on the bobbin-holder and having a portion extending into position to adapt it to be engaged by a bobbin placed on the holder, said latch being weighted to normally maintain it out of engagement with the detent on the holder, a plunger-rod slidable in the hollow rod and provided at its lower end with means for engaging the latch to rock the latter, a spring for normally retracting the plunger-rod away from the latch, and a weight on the bobbin-holder adapted to rock the latter downwardly to doff a spent bobbin therefrom and to thereafter return the bobbin-holder into position to be engaged by the pawl.

18. In a device of the type specified, the combination of an inclined runway, a disk-like member pivoted at the lower end of the runway and provided with detent-shoulders on its periphery, a spindle mounted on the disk, a pawl engaging the disk to hold it in position with the spindle aligned with the run-

way, a weighted latch extending across the spindle to adapt it to be engaged by a bobbin placed thereon to cause it to be rocked to release the pawl, said latch provided with a 5 detent-projection for engaging the second shoulder on the disk to maintain the spindle in erect position, manually-operable means for rocking the latch to release the disk, and a weighted arm acting to turn the disk to 10 tilt the spindle into position to doff a spent bobbin and to thereafter return the disk to first position to be engaged by the pawl.

19. In a device of the type specified, the combination of a tiltable spindle for holding 15 bobbins, means for normally retaining the spindle in position for the bobbin to deliver its material, means for releasing said retaining-means, and means for tilting the spindle into inverted position upon release of the 20 retaining-means to cause the spent bobbin to slide-off therefrom under the action of gravity.

In testimony whereof I hereunto affix my
signature.

25 GEORGE N. TAYLOR.
